UNITED STATES PATENT OFFICE.

J. L. BRIDGE AND W. B. LODGE, OF VERNON, NEW YORK.

FORMER FOR FORMING SEAMLESS FELT CAPS.

Specification of Letters Patent No. 28,149, dated May 8, 1860.

To all whom it may concern:

Be it known that we, J. L. BRIDGE and W. B. LODGE, both of Vernon, in the county of Oneida and State of New York, have invented a new and useful Machine for Forming Woolen Cap-Bodies Without a Seam; and we do hereby declare that the following is a full, clear, and exact description of the same, reference being had to the annexed drawings, making a part of this specification, in which—

Figure 1, is a plan or top view of our invention. Fig. 2, a side elevation of ditto; Fig. 3, a detached view of the former of ditto, with a cap body thereon bisected.

Similar letters of reference indicate corresponding parts in the several figures.

This invention has for its object the forming of cap bodies in a single piece or without 20 a seam and at one operation.

The invention consists in the employment or use of a flexible or sectional former so arranged that it may, after the body is formed on it, be elongated so as to be capable of being withdrawn from within the body.

To enable those skilled in the art to fully understand and construct our invention we will proceed to describe it.

A represents a vertical shaft the lower end 30 of which is stepped in a metal bar B, secured to the under side of a table or base C, the shaft A, extending up through the base C, and having a hollow shaft D, fitted loosely on it. To the upper end of the shaft 35 D, there are attached two parallel curved bars E, the ends of which form bearings for inclined cones F. There are four of these cones, one at each end of each bar E, and each pair of cones is connected by gears G, 40 at their bases, and the base of one cone of each pair is provided with a toothed wheel H, which wheels are connected with a train of gear wheels I, which are operated by a heel J, on the upper end of shaft A, the 45 wheels I, having their axes attached to one of the bars E.

On the lower part of the shaft A, below the hollow shaft D, there is placed a toothed wheel K, which gears into a corresponding wheel L, the axis of which is attached to a bar M, underneath the table or base C, said bar being fitted loosely at one end to a vertical rod N, which forms the axis of a toothed wheel O, that is placed 50 loosely on it, said wheel O, being above the table or base C, and gearing into the wheel 55

L. The wheel O, performs the function of a gear and crank, and it is connected by a pitman P, to an arm Q, which is attached to the lower end of the hollow shaft D. 60

The position of the cones F, is shown clearly in Fig. 1, and it will be seen by referring to this figure, that their position in connection with their conical form will serve as a proper seat or bed for an oblate 65 spheroidal former R, the latter being fitted between the cones.

The former R, may be constructed of india-rubber, and inflated with air until it assumes the desired form, as shown clearly 70 in Figs. 1, and 3, or, it may be constructed of wood or other rigid material in sections, in such a way as to be capable of being extended in the direction of its axis and transformed from an oblate to a very prolate 75 spheroid. The former R, when adjusted to the machine, that is to say, fitted between the cones F, is of the form of an oblate spheroid, and if the former is constructed of 80 india-rubber it is inflated with air, and the orifice a, closed by a valve, see Fig. 2, in which the orifice is shown at the center of one side of the former.

The operation is as follows. The former R, being adjusted in proper position 85 between the cones F, the shaft A, is rotated by any convenient power and a rotary motion is transmitted from shaft A, to the cones F, through the medium of the gearing I, J, H, G, the cones rotating in the 90 direction indicated by the arrows in Fig. 1. The cones F, cause the former R, to rotate in the direction indicated by the arrow marked upon it, and in addition to this movement it has a horizontal oscillating, or 95 vibrating movement given it, through the medium of the gearing L, O, pitman P, and arm Q; the cones F, and bars E, of course having the same oscillating movement as the latter transfers said movement to the 100 former R. As the former R, is thus rotated, and oscillated or vibrated, the wool is distributed evenly upon it from a carding machine, and when the former R, is fully 105 covered with the wool to a requisite thickness, the machine is stopped, and the former R, removed from the machine, the former being then elongated, so that it can be drawn out from within the cap body through a central opening a*, made for the purpose at 110 one side of the body, see Fig. 3, in which the cap body is designated by b*. This

elongation of the former R, is due to its flexibility or yielding capacity. If the former be constructed of india-rubber, its valve is opened and the wind or air allowed to escape, in order to admit of its ready elongation and withdrawal from within the body. If of wood or other rigid material the sections are jointed to admit of a similar elongation. The vibratory movement of the bars E, cones F, and former R, may be stopped at any time by throwing the wheel L, out of gear with wheel K.

The cap bodies thus formed require no seam, they may be hardened at once into proper state for use. All other modes of forming cap bodies of a bell shape, or those which have a top of larger diameter than the

lower portion that is fitted on the head, have hitherto, so far as we are aware, been constructed of two parts, and then united by 20 felting or otherwise.

Having thus described our invention, what we claim as new and desire to secure by Letters Patent is:

The employment or use of a flexible, or 25 sectional former R, constructed so as to be capable of being elongated or transformed from an oblate to a prolate spheroid, substantially as and for the purpose specified.
